AUTOMATIC TELEPHONE SYSTEM

Eugen Jauch, Berlin-Siemensstadt, Germany, assignor to Fides Gesellschaft fur die Verwaltung und Verwertung von gewerblichen Schutzrechten m. b. H., Berlin, Germany

Application November 21, 1938, Serial No. 241,506
In Germany November 22, 1937

14 Claims. (Cl. 179—26)

The present invention relates to automatic telephone systems with main and sub-exchanges in which for the purpose of making a connection between two subscribers of the same sub-exchange (an internal connection) the selectors are set with the aid of the main exchange.

Arrangements are already known in which for making internal connections two selectors are provided in the sub-exchange on a junction line extending between the sub-exchange and the main exchange of which one serves to connect the calling subscriber to the junction line leading to the main exchange, while the other is set by dialled impulses to select the desired subscriber in the sub-exchange. In these systems a considerable number of switching devices are necessary in the sub-exchange, in particular a feeding battery, since only the setting of the selector which selects the desired subscriber is done from the exchange while the selector for connecting the calling subscriber is controlled by local current from the sub-exchange.

Further arrangements have been proposed in which such a great expense on switching devices in the sub-exchange is avoided in that the control of the selector serving to connect the calling subscriber is also done from the main exchange. Here, however, two junction lines are used between the main exchange and the sub-exchange in order to make the internal connection, and the calling subscriber is connected to the first junction line over a selector included in the junction line while the selection of the desired subscriber is carried out by setting the selector in the second junction line.

The present invention describes a method of controlling both selectors from the main exchange over a single junction line.

In order to do this, after the setting of the selector which serves to connect the calling subscriber to the junction line has been controlled over the junction line from the main exchange, in dependence upon the characterizing of a connection with a subscriber of the same sub-exchange switching devices in the main exchange come into effect and influence switch means in the sub-exchange over the junction line by which a reversal of connections is produced in the sub-exchange so that instead of the selector which is set on the calling subscriber, the selector serving to select the desired subscriber is brought under the influence of the main exchange, over the same junction line.

The invention also relates to automatic telephone systems including main and sub-exchanges

in which the separation of traffic directions and the sending of impulses for setting selectors in the sub-exchange is done in the main exchange.

In systems in which the traffic directions are separated in the main exchange, the sending out of impulses from the main exchange to the sub-exchange controls, either the selector in the sub-exchange which serves to select the desired sub-exchange subscriber, or in addition, the selector which carries out the connection of the calling sub-exchange subscriber by means of impulses controlled by the main exchange.

In systems of the first kind the sending out of impulses to build up incoming connections and internal connections to the desired subscriber in the sub-exchange is done either by switching mechanism, which, on its setting according to a certain characterization by an impulse receiver influenced by the calling subscriber of the main exchange or similarly by a switching discriminator set for the purpose of separating the traffic directions from the calling subscribers of the sub-exchange, sends impulses to the sub-exchange, or by means of repeating devices which pass on the impulses from the calling subscriber connected to the main exchange or otherwise, according to the separation of the traffic direction by the impulse selection of the calling subscriber connected to the sub-exchange, sends back the impulses.

In systems of the second kind the impulses necessary for setting the selector for the purpose of connecting the calling subscriber and for the purpose of selecting the desired subscriber, are produced either by the setting of different switching mechanism in the main exchange or the same switching mechanism serves to produce impulses for connecting the calling subscriber and for the selection of the desired subscriber; and actually either only in so far as it produces the impulses on the setting up of an incoming connection in dependence on the setting of a dial impulse receiver, while the impulse sending for selecting the desired subscriber for internal connections is done by direct sending back of the selecting impulses after the traffic discrimination, or the switching mechanism also sends the impulses for building up the internal connection. In the latter case it must be set for all impulse sending and actually only for the connection of the calling subscriber in the first place and then for the selection of the desired subscriber according to a certain characterization from a switching discriminator influenced to separate the traffic directions of the calling subscribers.

The present invention describes another method which consists in connecting the operating magnets by switching devices influenced in the main exchange in dependence on the setting of a switching mechanism in an operating circuit controlled by the dial impulses for the separation of the traffic directions or in an automatic operating circuit to produce impulses for setting the selector in the sub-exchange.

In the arrangement according to the invention, by using for example, the switching mechanism for separating traffic directions and producing impulses for selecting the desired sub-exchange subscriber in the making of an internal connection, the advantage is produced in that the expense on special switching mechanism is avoided if the switching technique does not allow the known repeated use of the switching mechanism serving to connect the calling subscriber. This is the case, for example, when this switching mechanism by means of its setting, characterizes the calling subscriber in the main exchange for some purpose or other, e. g., metering his conversation. In this arrangement three switching mechanisms are necessary, namely, for connecting the calling subscriber, for separating the traffic directions, and for selecting the desired subscriber. By using the arrangement according to the invention, however, the last two functions can, for example, be carried out by a single switching mechanism so that altogether only two switching mechanisms are necessary.

In systems in which the calling subscriber is connected, not by means of an impulse sent out by a switching mechanism, but by the selection of the desired subscriber by such a switching mechanism then, in general, only a single switching mechanism is necessary; and this is also true in the reverse case.

The invention also relates to automatic telephone systems having main and sub-exchanges in which connections between two subscribers of the same sub-exchange are made with the aid of the main exchange over a junction line extending between the main and sub-exchange.

In these systems special difficulties arise in effecting the further switching operations necessary for building up the connection over the connecting line between the main and sub-exchange after the selection of the desired exchange subscriber. These switching operations in particular concern the sending out of the calling current disconnection of the calling current, and maintaining of the connection until the desired subscriber replies. If, for example, the calling subscriber is connected after the selection of the desired subscriber to the same junction line between the main and sub-exchange to which also the desired subscriber is to be connected, then on using the usual call connections the calling current is disconnected as soon as it is sent out over the speaking loop of the calling subscriber. This speaking loop must therefore be interrupted after the selection of the desired subscriber in order to prevent this premature disconnection of calling current. The arrangement is not, however, favorable for this interruption since the existence of the speaking loop is necessary in order to maintain the connecting path which has been set up.

In some systems, therefore, the calling sub-exchange subscriber is only disconnected during the sending out of calling current to the sub-exchange

from the junction line, and during this time the relay in the main exchange serving to maintain the connection is transitorily connected in the holding circuit so that during each pause in the calling current the calling subscriber is again connected to the junction line so as again to bring the relay serving to maintain the connection, under its influence. Since such arrangements, disregarding the extra expense on switching devices, are inconvenient on account of the calling subscriber having no influence in the course of the switching operations during the period in which he is completely disconnected, other arrangements have been proposed in which after the selection of the desired subscriber the junction line between the main exchange and the sub-exchange is interrupted so that the circuit for maintaining the connection extends over one conductor under the influence of the calling subscriber and the calling current extends to the desired subscriber over the other conductor.

Further, arrangements have been developed which avoid a premature disconnecting of the calling current by the calling subscriber by having them not brought about by a simple loop formation but by a transitory production of impulses which is initiated on the lifting up of the receiver so that the calling subscriber already connected to the junction line cannot disconnect the calling current, but this can only be done by the desired subscriber who, on his reply, by lifting up his receiver produces the necessary impulse. This arrangement requires a special construction on the subscriber's set in order to bring about a transitory production of an impulse when the receiver is removed.

The present invention indicates another method which according to which switching arrangements come into effect after the characterizing of the desired sub-exchange subscriber, which by influencing the switching devices in the sub-exchange so change the resistance ratio in the loop of the calling subscriber that over this, switch means in the main exchange serving to maintain the connection are operated, while switching means in the same circuit for disconnecting the calling current only come into effect on the reply of the desired subscriber.

The invention also relates to automatic telephone systems with main and sub-exchanges in which connections between subscribers of the same sub-exchange are metered by meters arranged in the main exchange.

If in the making of such a connection the calling subscriber accidentally dials his own call number instead of the call number of the desired subscriber the operation of his meter arranged in the main exchange is prevented.

Arrangements are already known for this purpose, for several subscribers connected to a common junction line in which when the called subscriber picks up his receiver an impulse is produced by which a metering relay in the junction line in the corresponding exchange is energized and influences the meter in the main exchange associated with the calling subscriber. If in this arrangement the calling subscriber dials his own call number then since the calling subscriber already has his receiver on the common connecting line removed, such an impulse for influencing the metering relay cannot arise; accordingly there is no metering action in the main exchange.

The present invention without undertaking any special construction of the subscriber's loop

prevents a metering action when the subscriber dials his own call number in that by the setting of the switch mechanism for characterizing the desired subscriber in agreement with the switching devices for characterizing the calling subscriber switch means in the main exchange are influenced which prevent an operation of the meter associated with the calling subscriber in the main exchange.

Referring to the drawings, Fig. 1 is a circuit diagram of the apparatus at the sub-exchange, and Figs. 2 and 3 combined disclose a circuit diagram of the apparatus at the main exchange.

As an embodiment the sub-exchange UA is shown in the drawings which is connected over a junction line *av/bv* with a main exchange HA. Two selectors AS and LW in the sub-exchange are associated with this junction line by which the selector AS (wipers *as1/as3*) is set on a calling subscriber while the other selector LW (wipers *lw1/lw4*) serves to select the desired subscriber. The control of the two selectors is done from the main exchange HA. This takes place in such a manner that on the call of a subscriber in the sub-exchange UA the call relay X in the main exchange is first energized over the junction line by which a switch mechanism KW (wipers *kw1/kw5*) is set in operation and while it is stepping on, produces impulses which are sent out to the sub-exchange UA in order to set the selector AS in this exchange on the calling subscriber. When this has been done, by means of a test relay P in the main exchange energized over the junction line the mechanism KW in the main exchange is brought to a standstill and the impulse sending interrupted: the selector AS in the sub-exchange UA, thus remains on the contacts of the calling subscriber. On a setting of the switching mechanism KW in the main exchange HA to correspond with the calling subscriber the meter in the main exchange corresponding to the calling subscriber is connected at the same time. The calling subscriber can now, by sending out impulses, set up the desired connection and in fact can make connections over the main exchange HA as well as connections to subscribers in the sub-exchange. In order to separate these two traffic directions in the main exchange a further switch mechanism MW (wipers *mw1/mw6*) is provided which is stepped on by the individual impulse series sent out from the calling subscriber. When by means of these impulse series a connection to a subscriber of the same sub-exchange is characterized the selector of the main exchange which is set in preparation by these impulse series, is released and after the characterizing of the desired subscriber, impulses are sent out from the switch mechanism MW, serving to separate the traffic directions, to the sub-exchange UA, in order to set the selector LW serving to select the desired subscriber of this subscriber's set. After the impulses have been sent out the sending out of the calling current to the desired subscriber and on his reply the completing of the speaking connection between the calling and the called subscriber takes place. It will be seen that all the switching operations for the setting up of this connection are controlled from the main exchange HA so that the feeding current for operating the switching devices during the setting up of a connection is completed in the main exchange. In the sub-exchange UA there is no feeding current battery.

Setting up an internal connection

Since the scope of the invention is more especially concerned with the setting up of a connection between two subscribers of the same sub-exchange, this will now be described in detail.

When the system is not in use the relays T1 to T3 in the sub-exchange UA are energized over the lead *av* of the junction line; and this circuit actually extends over: earth, battery, relay X, contact 116x, wiper *kw3* of the switch mechanism KW in setting 0, contacts 25r2, 22s, 23u2, 24m, lead *av* of the junction line, contacts 13r12, 10u1, wiper *lw1* of the selector LW in setting 0, wiper *as1* of the selector AS in setting 0, relays T1 to T3, earth. In this circuit only the relays T1 to T3 are energized so that, as shown, the contacts of these relays are closed in the normal condition of the system. All the subscribers of the sub-exchange UA are accordingly multiplied to the conductor *av* of the junction line.

When now for example the subscriber *Tn1* lifts up his receiver the following circuit is made: earth, battery, relay X, contact 116x, wiper *kw3* of the switch mechanism KW in setting 0, contacts 25r2, 22s, 23u2, 24m, conductor *av* of the junction line, contacts 13r12, 10u1, wiper *lw1*, of the selector LW in setting 0, wiper *as1* of the selector AS in setting 0, wiper *lw3* of selector LW in setting 0, wiper *as3* of the selector AS in setting 0, resistance *W11*, subscriber *Tn1*, contact 18t1, wiper *as2* of the selector AS in setting 0, contacts 7u1, 6r12, 8u1, relay *R1*, earth. In this circuit the relay X operates and connects itself in the holding circuit over its contact 117x, the resistance *W11* and the wiper *kw1* of the switch mechanism KW in setting 0. By opening the contact 116x, the normally existing circuit for the relays T1 to T3 mentioned previously is interrupted so that now over the contact 4t1 the rotary magnet *Das* of the selector AS in the sub-exchange is connected to the lead *bv* of the junction line. Over the lead *bv* the following circuit is made: earth, battery, winding I of the relay K, wiper *kw2* of the switch mechanism KW in setting 0, contacts 72q, 38y, lead *bv* of the junction line, contacts 5u1, 4t1, contact 3dlw of the rotary magnet *Dlw*, wiper *lw4*, of the selector LW in setting 0, contact 17t1, rotary magnet *Das* of the selector AS, earth. In this circuit only the relay K operates so that the following circuit is set up: earth, battery, rotary magnet *Dkw*, contacts 124p, 111k, 112q, 133a, earth. In this circuit the rotary magnet *Dkw* is influenced so that the switch mechanism KW executes a single step. The rotary magnet *Dkw* on its energizing closes the contact 30dkw so that over this contact and the resistance *W14*, the winding I of the relay Y is energized. By the closing of the contact 39y the following circuit is set up: earth, battery, resistance *W14*, contacts 34q, 39y, lead *bv* of the junction line, contacts 5u1, 4t1, contact 3dlw of the rotary magnet *Dlw*, wiper *lw4* of the selector LW in setting 0, contact 17t1, rotary magnet *Das* of the selector AS operates and steps on the selector AS by a single step. In the main exchange HA by the opening of the contact 75y on the energizing of the relay Y the relay K is deenergized so that by the opening of contact 111k, the rotary magnet *Dkw* of the switch mechanism KW in the main exchange is disconnected. As a result, contact 30dkw is also opened so that relay Y is deenergized and by the opening of the

contact 39_y the rotary magnet *Das* of the selector AS in the sub-exchange is disconnected. If the calling subscriber *Tn1* has not yet been reached by the selector AS the interaction between the relays K and Y and the rotary magnet *Dkw* begins again in order to step on the switch mechanism KW in the main exchange and the selector AS in the sub-exchange. Since, however, the calling subscriber *Tn1* has already been reached after a single step of the selector AS in the sub-exchange UA, after this stepping motion, the following circuit is made: earth, battery, resistance *Wi4*, contact 29*dkw* of the rotary magnet *Dkw*, winding I of the relay A, windings II and I of the relay P, wiper *kw3* of the switch mechanism KW in settings 1 to 11, contacts 25*r2*, 22*s*, 23*u2*, 21*m* and 20*k*, lead *av* of the junction line, contacts 13*r2*, 10*u1*, wiper *lw1* of the selector LW in setting 0, wiper *as1* of the selector AS in setting 1, subscriber's loop *Tw1*, wiper *as2* of the selector AS in setting 1, contacts 7*u1*, 6*r12*, 8*u1*, relay *R1*, earth.

In this circuit the relay P at once operates, and after the short-circuiting of the high resistance winding I over the contact 32*p* in the above mentioned circuit, the relay A is energized. On the opening of the contact 124*p* further operation of the rotary magnet *Dkw* is prevented. Relay K is maintained energized over: earth, battery, winding I of relay K, wiper *kw2* of switch mechanism KW in settings 1 to 11, contact 75*y*, wiper *kw1* of the switch mechanism KW in settings 1 to 10, earth.

In the sub-exchange UA the relay *R1* is transitorily energized in the above mentioned energizing circuit of the relay P in two stages: it operates the contacts marked *r12*. In this way the short circuit for the windings I and II of the relay *U1* at the contacts 13*r12* and 6*r12* is transitorily removed so that the relay *U1* is also energized in the circuit of the relay *P1* described. By closing the contact 9*u1* the conductor *bv* is switched through to the calling subscriber, while by the opening of the contact 8*u1* the relay *R1* is disconnected. The short-circuiting of the windings I and II of the relay *U1* does not take place, however, since the contacts 7*u1* and 10*u1* are open.

In the main exchange HA, in the meantime, after the energizing of the relay P by the closing of the contact 56*p*, a bridge is connected for the speech conductor over the windings II and III of the relay K since the preselector VW is set into operation in known manner and hunts for a free connecting line, for example to a first group selector in the main exchange. If such a line is found, then in known manner relay T is energized and stops the preselector VW. Over the wiper *kw4* of the switch mechanism KW which together with the selector AS in the sub-exchange UA rests on the contact 1, the meter *Z1* of the calling subscriber in the main exchange HA is connected. Further, in the main exchange after the energizing of the relay A the following circuit is completed: earth, battery, winding III of the relay P, contact 86*p*, winding I of the relay F, contacts 79*a*, 78*y*, 72*k*, earth. In this circuit the relay F is energized. Moreover, over the contact 102*a* the following circuit is completed: earth, battery, winding I of the relay C, contact 88*h11*, wiper *mw3* of the switch mechanism MW in setting 0, contacts 96*j*, 99*m*, 97*v*, winding II of the relay C, contact 102*a*, earth. In this circuit the relay C is energized.

If the calling subscriber *Tn1* wishes to speak to the subscriber *Tn10* in this own sub-exchange 75

UA he must select the number 403 222/0. The first six trains of impulses influence the individual dial impulse receivers in the main exchange one after another and at the same time 5 the switch mechanism MW, while by means of the last digit 0 only the switch mechanism MW in the main exchange is operated.

The switching operations which are carried out by the individual digits of the above mentioned 10 number are as follows:

By means of the first impulse series consisting of four impulses the circuit of the relay A energized over the subscriber's loop is interrupted four times so that by the corresponding interruption 15 of the bridge across the windings II and III of the relay K at the contact 54*a* the first dial impulse receiver in the main exchange is influenced in known manner. Moreover, by the opening and closing of the contact 133*a* the rotary magnet *Dmw* of the switch mechanism MW is energized four times over: earth, battery, rotary magnet *Dmw* of the switch mechanism MW, contacts 126*s*, 127*c*, 111*k*, 112*q*, 133*a*, earth. The switch mechanism MW reaches its fourth contact setting so that accordingly its wiper *mw3* for example comes to rest on the contact *n1*. During the impulse series the relay V is energized as a slow relay by the connection of its winding I over the contact 117*dmw* of the rotary magnet *Dmw*, so that over contact 98*v* and the contact 75*c* a holding circuit for the windings I and II of the relay C is closed during the impulse series. At the end 30 of the impulse series the relay V restores with a delayed release so that now the following circuit is completed: earth, battery, winding I of the relay *H1*, resistance *Wi4*, contact 87*h12*, wiper *mw3*, of the switch mechanism MW on the contact *n1*, contacts 96*j*, 99*m*, 97*v*, winding II of the relay C, contact 102*a*, earth. In this circuit the 35 relay C is maintained energized. Also the relay *H1* on the first step operates its contact indicated by "h11". A holding circuit is closed for the relay *H1* over: earth, battery, winding I of the relay *H1*, resistance *Wi4*, winding II of the relay *H1*, contacts 134*c*, 94*h11*, earth.

The second impulse series consisting of ten impulses brings about a setting of the second dial impulse receiver in the main exchange in corresponding manner by the energizing and deenergizing of the relay A and a further setting of 50 the switch mechanism MW, so that this moves from its zero setting of its wiper *mw3* on to the contact *n2*. The relay V is energized during the 55 impulse series in the same way so that during this period the above mentioned holding circuit for relay C is closed. When at the end of the impulse series the relay V is disconnected the following circuit is completed: earth, battery, winding I of the relay *H1*, contacts 81*h11*, 83*h21*, wiper *mw3* of the switch mechanism MW on the contact *n2*, contacts 96*j*, 99*m*, 97*v*, winding II of the relay C, contact 102*a*, earth. In this circuit the relay C remains energized while relay *H1* energizes for the second time and operates its contact indicated by "h12". The energizing in the second stage is maintained in the circuit already described over contacts 94*h11* and 134*c*.

The next impulse series consisting of three impulses influences the third dial impulse receiver in the same manner in the main exchange as well as the switching mechanism MW till the latter reaches the contact *n3*. The energizing of the relay C is maintained by means of the relay V energized during the impulse series in the manner already described. At the end of the impulse

series, the relay V is again disconnected so that the following circuit is completed: earth, battery, winding I of relay H2, resistance Wi15, contacts 84h22, 86h12, wiper mw3 of the switch mechanism MW on the contact n3, contacts 96j, 99m, 97v, winding II of the relay C, contact 102a, earth. The relay C remains energized in this circuit when the relay H2 is energized in the first stage so that it operates its contact indicated by "h21". A holding circuit for the relay H2 extends over earth, battery, winding I of the relay H2, resistance Wi15, winding II of the relay H2, contacts 93h21, 88h11, earth.

The fourth impulse series sent out by the subscriber which consists of two impulses causes a fourth dial impulse receiver in the main exchange to be influenced and the switch mechanism MW to be displaced by two steps so that the wiper mw3 reaches the contact n4. The relay C also remains energized since the relay V is again energized during the impulse series so that after the completion of the impulse series in view of the deenergizing of the relay V the following circuit is completed: earth, battery, winding I of the relay H2, contacts 82h21, 85h3, wiper mw3 of the switch mechanism MW on the contact n4, contacts 96j, 99m, 97v, winding II of relay C, contact 102a, earth. The relay C remains energized in this circuit while the relay H2 is now operated in the second stage. Accordingly, it operates its contact indicated by "h22". A holding circuit for maintaining the relay H2 energized in the second stage, extends over: earth, battery, winding I of relay H2, resistance Wi15, winding II of relay H2, contacts 93h21, 94h11, earth.

The fifth impulse series consisting of two impulses influences the fifth dial impulse receiver and moreover steps on the switch mechanism MW by two steps to the contact n5. Over this wiper after the deenergizing of the relay V and the completion of the impulse series the following circuit is made: earth, battery, relay H3, contact 90h22, wiper mw3 of the switch mechanism MW on the contact n5, contacts 96j, 99m, 97v, winding II of the relay C, contact 102a, earth. The relay C remains energized in this circuit; moreover, there follows an energizing of the relay H3 which is maintained in the following circuit: earth, battery, relay H3, contacts 90h22, 132h3, resistance Wi13, contact 130f and wiper mw6 of the switch mechanism MW in settings 1-11, contact 72k, earth.

By the last impulse series consisting of two impulses the sixth dial impulse receiver is set in the main exchange for the purpose of discriminating between the traffic directions, and the switch mechanism MW is displaced by two steps so that its wiper mw3 reaches the contact i. After the deenergizing of the relay V energized during the impulse series, the following circuit is completed: earth, battery, winding I of relay J, contact 89h3, wiper mw3 of the switch mechanism MW on the contact i, contacts 96j, 99m, 97v, winding II of relay C, contact 102a, earth. On the energizing of relay J the above described circuit extending over the wiper mw3 of the switch mechanism MW is interrupted and on the closing of the contact 105j a circuit is formed over the wiper mw4 of the switch mechanism MW which extends over: earth, battery, winding I of relay J, wiper mw4 of the switch mechanism MW in setting i, contacts 105j, 99m, 97v, winding II of relay C, contact 102a, earth. In this circuit relays J and C are maintained energized.

On the opening of contact 57j the bridge across the windings II and III of relay K is broken so that the selector which has been set in the main exchange is released.

5 By means of the impulses sent out up to this point the fact that the calling subscriber Tn1 wishes to make a connection to a subscriber in his own sub-exchange UA has been indicated. He must now send a further impulse series, in order to select the desired subscriber which in the present case since it is the subscriber Tn10 who is desired, consists of ten impulses. This impulse series only influences the switch mechanism MW in the main exchange; and actually this is stepped on from the previously reached setting (contact i) so that the wiper mw4 of the switch mechanism MW reaches the contact 9 owing to this impulse series. During the impulse series the relay V is energized for the purpose of maintaining the relay C energized, as has been described several times already, so that after the completion of the impulse series, in view of the deenergizing of the relay V the following circuit is completed: earth, battery, winding III of relay S, relay U2, wiper mw4 of switch mechanism MW on the contact 9, contacts 105j, 99m, 97v, winding II of relay C, contact 102a, earth. In this circuit the relay C is maintained energized and the relay U2 is operated. The energizing of relay S does not take place in this circuit. After the energization of the relay U2 the winding II of the relay C is short circuited so that it restores. The relay J on the other hand remains energized in the following circuit: earth, battery, windings I and III of relay J, contacts 101j, 102a, earth. The relay U2 is maintained energized over: earth, battery, winding III of relay S, relay U2, wiper mw4 of the switch mechanism MW on the contact 9, contacts 103u2, 101j, 102a, earth.

40 Meanwhile, in view of the energizing of the relay U2 the short circuit of resistance Wi3 at contact 23u2 is removed and moreover by the opening of contact 41u2 the earth connected to the lead bv over the winding III of relay A has been disconnected so that in the sub-exchange UA the relay U1 is deenergized. In this way, the following circuit is completed: earth, battery, resistance Wi4, contact 29dkw of the rotary magnet Dkw, winding I of relay A, contacts 31f, 32p, wiper kw3 of the switch mechanism KW in settings 1-11, contacts 25r2, 22s, resistance Wi3, contact 20k or 21m, lead av, contacts 13r12, 10u1, wiper lwl of selector LW in setting 0, wiper as1 of selector AS in setting 1, subscriber Tn1, wiper as2 of selector AS in setting 1, contacts 7u1, 6r12, 8u1, relay R1, earth. In this circuit relay A is maintained energized while the relay R1 is energized in the first stage and operates its contacts indicated by "r11." On the closing of the contact 19r11 the rotary magnet Das of the selector AS in the sub-exchange UA is short-circuited and by the opening of the contact 1r11 the short circuit for the rotary magnet Dlw of the selector LW is removed so that now in the sub-exchange UA the rotary magnet Dlw is ready for operating and the conductor bv in the junction line is connected to the main exchange.

70 Meanwhile, in the main exchange HA by the opening of the contact 134c after the short-circuiting of the winding II of relay C the relay H1 is disconnected, and by the opening of contact 94h11 brings about the deenergizing of relay H2. By the opening of contact 90h22 the relay H3 is disconnected. After the closing of

contacts 91c and 92h21 the relay H1 is again energized over: earth, battery, winding I of relay H1, resistance Wi4, winding II of relay H1, contacts 91c, 92h21, wiper mw2 of switch mechanism MW in setting 1—11, contact 100dmw of the rotary magnet Dmw, earth. By the closing of the contact 108h3 after the deenergizing of relay H3 the following circuit is completed: earth, battery, rotary magnet Dmw of the switch selector MW, contacts 126s, 125j, 111k, 112q, 110u2, 108h3, earth. In this circuit the rotary magnet Dmw is energized so that the switch mechanism MW executes a further step. On the energizing of the rotary magnet Dmw an energizing of the relay Y also takes place over: earth, battery, resistance Wi4, contact 28u2, contacts 27dmw of the rotary magnet Dmw, winding I of the relay Y, earth. By the closing of the contact 39y the following circuit is completed: earth, battery, resistance Wi4, contacts 34q, 39y, lead bv of the junction line, contacts 5u1, 4t1, rotary magnet Dlw of the selector LW in the sub-exchange UA, contact 19r11, earth. The rotary magnet Dlw operates in this circuit and steps on the selector by one step. At the same time as the stepping motion of the switch mechanism MW in the main exchange the selector LW in the sub-exchange UA is accordingly moved one step. This stepping of the selector LW and the switch mechanism MW, which in the manner already described is brought about by the alternate play between the relays K and Y in connection with the rotary magnet Dmw of the switch mechanism MW, continues until the desired subscriber has been reached. In the present case the stepping action ceases after a single step. After one stepping movement the wiper mw5 of the switch mechanism MW reaches the contact s so that over this wiper the following circuit is completed: earth, battery, windings III and II of relay S, wiper mw5 of the switch mechanism MW on the contact s, contacts 103u2, 101j, 102a, earth. In this circuit the relay S is energized so that by the opening of contact 126s, the rotary magnet Dmw of the switch mechanism MW is disconnected and further stepping of the switch mechanism MW and thus also the selector LW in the sub-exchange UA is suppressed.

In the sub-exchange UA after the stepping of the selector LW the short circuit for the resistance Wi2 is removed at the wiper lw1 so that the relay R1 can be maintained energized over the subscriber's loop of the calling subscriber Tn1 and this resistance Wi2 only in the first stage, even when the resistance Wi3 is short-circuited. The maintaining of the connection set up depends upon the calling subscriber in the following circuit: earth, battery, resistance Wi4, contact 29dkw, winding I of the relay A, contacts 31f, 32p, wiper kw3 of the switch mechanism KW in settings 1—11, contact 25r2, winding II of relay J, resistance Wi3, contact 20k or 21m, lead av of the junction line, contacts 13r12, 10u1, resistance Wi2, contact 12dlw of the rotary magnet Dlw, wiper as1 of the selector AS in setting 1, subscriber Tn1, wiper as2 of the selector AS, in setting 1, contacts 7u1, 6r12, 8u1, relay R1, earth. In this circuit the relays A and J are maintained energized by the calling subscriber and hence, the connection is maintained.

Meanwhile, in the sub-exchange after the energizing of the relay S, before the slow relay U2 restores after the stepping on of the switch mechanism MW, the following circuit is completed: earth, battery, windings I and II of the relay

R2, contacts 118s, 119c, 122u2, earth. The relay R2, by closing its contact 24r2, connects calling current to the lead av of the junction line which reaches the desired subscriber over the following circuit: earth, battery, ringing current, resistance Wi8, contact 24r2, winding II of relay J, resistance Wi3, contact 20k or 21m, lead av of the junction line, contacts 13r12, 10u1, wiper lw1 of the selector LW in setting 1, subscriber Tn10, wiper lw2 of the selector LW in setting 1, contacts 7u1, 6r12, 8u1, relay R1, earth. After the release of the relay U2 the further extension of the call results by the energizing of the relay R2 over: earth, battery, windings I and II of relay R2, contacts 118s, 119c, 121u2, slow interrupter LU, earth. During the sending out of calling current by each operation of relay R2 the energizing current extending over the junction line and contact 25r2 passes over the contact 24r2 and resistance Wi8, so that during the sending out of the calling current the maintaining of the connection by energizing the winding II of the relay J is made possible over the loop of the calling subscriber. The calling subscriber therefore has the possibility during the sending out of calling current, of controlling the supervising the circuit for maintaining the connection without disturbing the sending out of calling current to the desired subscriber by means of his speaking loop. If he wishes to hang up the receiver, then in view of the interruption the loop connection is released. If the desired subscriber replies during a pause in the calling current, by lifting up his receiver the disconnection of calling current takes place by the completion of the following circuit: earth, battery, resistance Wi4, contact 29dkw of the rotary magnet Dkw, winding I of the relay A, contacts 31f, 32p, wiper kw3 of switch mechanism KW in settings 1 to 11, contact 25r2, winding II of relay J, contacts 23u2, 20k or 21m, lead av of the junction line, contact 13r12, 10u1, wiper lw1 of the selector LW in setting 1, subscriber's loop Tn10, wiper lw2 of the selector LW in setting 1, contacts 7u1, 6r12, 8u1, relay R1, earth. If the reply takes place during the sending out of calling current the necessary battery potential is not connected over the contact 25r2 but over the contact 24r2 and resistance Wi8. In this circuit the relay R1 operates in the second stage so that at the contacts 6r12 and 13r12 the short circuit for the windings I and II of the relay U1 is removed. The relay U1 operates the circuit mentioned and connects the conductor bv by closing the contact 9u1. The relay R1 is disconnected by the opening of contact 8u1; the resistance Wi2 is short-circuited over the contact 11u1. The holding circuit for the relay U1 now extends over: earth, battery, resistance Wi4, contact 29dkw of the rotary magnet Dkw, winding I of relay A, contacts 31f, 32p, wiper kw3 of the switch mechanism KW in settings 1—11, contact 25r2, winding II of the relay J, contacts 23u2, 20k or 21m, lead av of the junction line, winding I of the relay U1, contact 11u1, contact 12dlw of the rotary magnet Dlw, wiper as1 of the selector AS in setting 1, calling subscriber Tn1, wiper as2 of the selector AS in setting 1, or wiper lw1 of the selector LW in setting 1, desired subscriber Tn10, wiper lw2 of the selector LW in setting 1, winding II of relay U1, contact 9u1, lead bv of the junction line, contacts 38y, 41u2, 43p, 45s, winding I of the relay M, earth. In this circuit the relay M operates. By the closing of contact 68m the winding I of relay S is short-circuited, so

that in view of the increase in current the meter Z_1 of the calling subscriber is influenced over: earth, battery, winding II of relay T, meter Z_1 , wiper $kw4$ of switch mechanism KW in setting 1, contacts $69s$, $68m$, $66j$, earth. Since on the operation of the relay M at contact $99m$ the holding circuit of the relay S is disconnected (earth, battery, windings III and II of relay S, wiper $mw5$ of switch mechanism MW on the contact s, contacts $105j$, $99m$, $97v$, winding II of relay C, contact $102a$ earth) the relay S restores. In view of the contact $118s$ a further influencing of the relay R2 and hence a further sending out of calling current, is prevented. The relay M is maintained after the deenergizing of relay S over: earth, battery, winding II of relay M, contact $131m$, resistance W_{13} , wiper $mw6$ of the switch mechanism MW in settings 1—11, contact $72k$, earth. The winding III of the relay A is connected to the conductor bv after the deenergizing of the relay S instead of the relay M which maintains the connection which is short circuited over contact $44s$. The relay J is, however, maintained energized over the windings I and II in the following circuit: earth, battery, windings I and III of the relay J, contact $101j$, $102a$, earth.

The control circuit for maintaining the connection which serves at the same time to feed both subscribers $Tn1$ and $Tn10$ is as follows: earth, battery, resistance W_{14} , contact $29dkw$ of the rotary magnet Dkw , winding I of the relay A, contacts $31f$, $32p$, wiper $kw3$, of the switch mechanism KW in settings 1—11, contacts $25r2$, $22s$, $23u2$, $20k$, lead av of the junction line, winding I of the relay $U1$, contact $11u1$, contact $12dlw$ of the rotary magnet Dlw , wiper $as1$ of the selector AS in setting 1 or wiper $lw1$ of the selector LW in setting 1, subscriber $Tn10$, wiper $lw2$ of the selector LW in setting 1, winding II of relay $U1$, contact $9u1$, lead bv of the junction line, contacts $38y$, $41u2$, $43p$, $44s$, winding III of relay A, earth. In this circuit the maintaining of relay A energized, in order to maintain the connection, is the standard method.

It should be noticed that after the deenergizing of the relay S after the reply of the desired subscriber $Tn10$ the switch mechanism MW is connected in its normal position and the following circuit is completed: earth, battery, rotary magnet Dmw , contacts $126s$, $129c$, $128h11$, $109u2$, $108h3$, earth. The energizing and deenergizing of the rotary magnet Dmw in this circuit is produced by the contact $128h11$ which on the energizing of the rotary magnet Dmw opens the contact $100dmw$ and thus disconnects the relay $H1$ whereby by the opening of the contact $128h11$ the rotary magnet Dmw is deenergized so that over contact $100dmw$ relay $H1$ is again connected. This alternate operation and release continues until the wiper $mw2$ of the switch mechanism MW has left the contact segment 1—11 so that further operation of relay $H1$ is prevented.

When at the end of the conversation both subscribers hang up their receivers the above described circuit for maintaining the connection is interrupted. In this way the relays A and $U1$ are immediately disconnected; relay J restores on the opening of contact $102a$. Finally, in a manner which is of no interest here, the relays F, P and M are disconnected so that the following circuit is completed: earth, battery, rotary magnet Dkw of the switch mechanism KW, contacts $124p$, $111k$, $112q$, $133a$, earth. By the continued energizing and deenergizing of the rotary magnet Dkw described in the case of the stepping move-

ment together with the relays K and Y, a stepping on of the switch mechanism KW takes place at the same time, as described above, over the contact $39y$ and the conductor bv of the junction line, impulses are sent out to the sub-exchange. By means of these impulses the rotary magnet Dlw of the selector LW is influenced so that the selector LW is stepped on in the sub-exchange. When this selector has reached its rest position the wiper $lw4$ of the selector LW stands in its zero position so that rotary magnet Dlw is short-circuited and further influencing by impulses from the main exchange is prevented. The relay X is disconnected when the wiper $kw1$ reaches the segments 1—10. Since the selector AS in the sub-exchange UA still has not reached its rest position the switch mechanism KW in the main exchange HA steps on past zero position by action of the relay K and sends further impulses to the sub-exchange UA, by which now over the conductor bv of the junction line the rotary magnet Das of the selector AS is operated. When this selector has also reached its rest position the normal circuit described at the beginning is completed and extends over: earth, battery, relay X, contact $116x$, wiper $kw3$, of the switch mechanism KW in setting 0, contacts $25r2$, $22s$, $23u2$, $20k$ or $21m$, lead av of the junction line, contacts $13r12$, $10u1$, wiper $lw1$ of the selector LW in setting 0, wiper $as1$ of the selector AS in setting 0, relays $T1$, $T2$, $T3$, earth. In this circuit only the relays $T1$ to $T3$ operate, and by opening the contact $4t1$ disconnect the rotary magnet Das of the selector AS from the conductor bv . Relay K can now no longer be energized over conductor bv so that the switch mechanism KW should it be in its normal position, is not stepped on any further. On the other hand, if the switch mechanism has not yet reached its normal position relay K is energized and deenergized over the wiper $kw2$ in setting 1—11 in combination with relay Y and the rotary magnet Dkw till the switch mechanism KW has reached its normal position.

45 Prevention of metering of the subscriber's number

Let us assume that the calling subscriber in making a connection to the desired subscriber $Tn10$ instead of the last digit 0 by mistake selects his own characterizing digit 1 in which case the metering of the connection should not take place. This is prevented by the following arrangement:

55 The switch mechanism KW after the connection of the subscriber $Tn1$ e. g. by the wiper $kw5$, rests on the contact 1 as described, while the switch mechanism MW previous to the selection of the subscriber's own digit rests for example, with its wiper $mw5$ on the contact i . When the calling subscriber now selects the digit 1, i. e. his own connection, the switch mechanism MW makes one step forward. Among other operations which take place the wiper $mw5$ reaches the setting 0 so that after the deenergizing of the relay V at the termination of the impulse series, the following circuit is made: earth, battery, winding III of relay S, contact $104v$, wiper $kw5$ of the switch mechanism KW in setting 1, wiper $mw5$ of the switch mechanism MW in setting 0, contacts $105j$, $99m$, $97v$, winding II of relay C, contact $102a$, earth. In this circuit the relay S operates while the relay C in contrast to the switching operations when the correct number is selected, remains energized. As a result the re-

lays H1, H2 and H3 do not restore as the contact 134c is maintained operated. The engaged signal is transferred to the winding II of relay A over the contacts 118s and 120c, and by means of the inductive effect of the relay A on the winding I, reaches the calling subscriber. Since the winding I of the relay M is short-circuited over the contact 40h3, the relay M is not influenced over the loop of the conductors av and bv in the usual way so that as the contact 68m is maintained open, a metering of the connection by the meter Z1 is prevented. Therefore by the agreement in the settings of the switch mechanisms KW and MW when the wrong called number is sent out the metering of such connections is prevented.

What is claimed is:

1. In a telephone system, two exchanges, means for completing a local connection between two subscribers' lines in one of said exchanges, a source of potential in the other of said exchanges, and means including but one two-conductor inter-exchange trunk line for connecting said source to said local connection to supply transmission current to both of said subscribers' lines. 20

2. In a telephone system, two exchanges, a trunk line connecting said exchanges, subscribers' lines terminating at one of said exchanges, a switch in said one exchange having access to said subscribers' lines, and means in the other of said exchanges responsive to a calling condition on one of said subscribers' lines for controlling said switch over said trunk line to connect with said one subscriber's line. 25

3. In a telephone system, two exchanges, a trunk line connecting said exchanges, subscribers' lines terminating at one of said exchanges, a switch in said one exchange having access to said subscribers' lines, and means in the other of said exchanges responsive to the initiation of a call by one of said subscribers' lines for transmitting impulses over said trunk line to said one exchange to operate said switch to search for said one subscriber's line. 35

4. In a telephone system, two exchanges, a trunk line connecting said exchanges, a discriminating device at one of said exchanges connected to said trunk line, subscribers' lines terminating at the other exchange, means for marking any one of said subscribers' lines, means in said other exchange operated to connect said trunk line successively with said subscribers' lines, said device responsive to the connection of the trunk line with the marked subscriber's line to halt the operation of said last means. 40

5. In a telephone system, a main exchange, a sub-exchange, a trunk line connecting said exchanges, two switches in the sub-exchange, means in the main exchange controlled by the initiation of a call from a subscriber's station in the sub-exchange for operating one of said switches over said trunk line to seize the calling line, means in the main exchange operated over the trunk line by the calling subscriber for designating the wanted line, and means in the sub-exchange operated over said trunk line by said last means whenever the designated line is in the same sub-exchange for connecting the other of said switches for operation over said trunk line. 55

6. In a telephone system, a main exchange, a sub-exchange, a trunk line connecting said exchanges, two switches in the sub-exchange, means in the main exchange controlled by the initiation of a call from a subscriber's station in the sub-exchange for transmitting one or more impulses 70

over the trunk line to the sub-exchange, a receiving circuit in the sub-exchange responsive to said impulses and operating one of said switches to connect with the calling line, means in the main exchange operated over the trunk line by the calling subscriber for designating the wanted line, means in the sub-exchange operated over said trunk line by said last means if the designated line is in said sub-exchange to alter said 10 receiving circuit to control the other of said switches, and means in the main exchange for then transmitting one or more impulses over the trunk line to cause said other switch to connect with the designated line. 15

7. In a telephone system, a main exchange, a sub-exchange, a trunk line connecting said exchanges, means for extending a connection from a calling subscriber's line in the sub-exchange over said trunk line to the main exchange, said connection containing a certain resistance, means in the main exchange operated over said connection by the calling subscriber for designating the wanted line, and means in the sub-exchange controlled by said last means for varying the value of said resistance if the designated line is in the same sub-exchange. 20

8. In a telephone system, a main exchange, a sub-exchange, a trunk line connecting said exchanges, a calling subscriber's line and a called subscriber's line terminating at the sub-exchange, switching apparatus at the sub-exchange operated to connect both of said subscribers' lines to said trunk line, two sources of potential at the main exchange, means for connecting one of said sources to said trunk line to supply control current thereover to the calling station, means for connecting the other of said sources to said trunk line to supply signalling current thereover to the called station, means responsive to the increase in said control current when the called station is bridged across the trunk line upon the subscriber thereat answering the call for interrupting said signalling current, and means responsive to an interruption of said control current by an operation at the calling station during the signalling of the called station for releasing the connection. 25

9. In a telephone system, a main exchange, a sub-exchange, a trunk line connecting said exchanges, two switches in the sub-exchange, means in the main exchange controlled by the initiation of a call from a subscriber's station in the sub-exchange for transmitting one or more impulses over the trunk line to the sub-exchange, a receiving circuit in the sub-exchange responsive to said impulses and operating one of said switches to connect with the calling line, means in the main exchange operated over the trunk line by the calling subscriber for designating the wanted line, a relay in the sub-exchange, means controlled by said last means to operate said relay if the designated line is in the sub-exchange, said relay thereupon altering said receiving circuit to control the other of said switches, means in the main exchange for then transmitting over the trunk line one or more impulses to cause said other switch to connect with the wanted line, means for signalling the called subscriber over the wanted line, and means controlled by said relay for interrupting said signalling responsive to the answering of the called subscriber. 30

10. In a telephone system, a main exchange, a sub-exchange, a trunk line connecting said exchanges, means in the main exchange for at 35

times determining the routing of calls from calling subscribers' stations in the sub-exchange and for at other times controlling switching equipment in the sub-exchange to extend calls to called subscribers' stations in said sub-exchange, said means including a step-by-step switch, a circuit for operating said switch in accordance with impulses received over said trunk line from a calling station in the sub-exchange to determine the routing of the call therefrom, another circuit for operating said switch to transmit impulses over said trunk line to control the switching equipment in said sub-exchange to extend a call to a desired one of the stations therein, and means controlled in accordance with the position of said step-by-step switch for rendering but one of said circuits effective.

11. In a telephone system, a main exchange, a sub-exchange, a trunk line connecting said exchanges, means in the main exchange for at times determining the routing of calls from calling subscribers' stations in the sub-exchange and for at other times controlling switching equipment in the sub-exchange to extend calls to called subscribers' stations in said sub-exchange, said means including a step-by-step switch, a circuit for operating said switch in accordance with impulses received over said trunk line from a calling station in the sub-exchange to determine the routing of the call therefrom, another circuit for operating said switch to transmit impulses over said trunk line to control the switching equipment in said sub-exchange to extend a call to a desired one of the stations therein, means controlled over one wiper of said switch at times rendering said first circuit effective, and means controlled over a different wiper of said switch at times rendering said other circuit effective.

12. In a telephone system, a main exchange, a sub-exchange, a trunk line connecting said exchanges, subscribers' lines terminating at the sub-exchange, means for transmitting impulses from a calling one of said subscribers' lines over said trunk line to designate the routing of the call from said calling line, a step-by-step switch in the main exchange, a first circuit for at times operating said switch in dependence upon the

impulses received over said trunk line to determine the routing of said call, a second circuit for at times operating said switch to transmit impulses over said trunk to control switching equipment in the sub-exchange to extend the call to one of the subscribers' lines in the same sub-exchange, and means controlled in accordance with the position of said step-by-step switch for determining which of said circuits shall be effective.

10 13. In a telephone system, a main exchange, a sub-exchange, a trunk line connecting said exchanges, a plurality of subscribers' lines terminating in the sub-exchange, a plurality of devices in the main exchange respectively corresponding to said subscribers' lines, means for operating said devices, means in the main exchange controlled by the initiation of a call by one of said subscribers' lines for connecting the corresponding device for operation by said means, means in the main exchange operated over the trunk line by the calling subscriber for designating the wanted line, and means operated whenever the designated line is the same as the calling line for preventing the operation of the device connected.

15 14. In a telephone system, a main exchange, a sub-exchange, a trunk line connecting said exchanges, a plurality of subscribers' lines terminating in the sub-exchange, a plurality of devices in the main exchange respectively corresponding to said lines, a switch in the sub-exchange and a corresponding switch in the main exchange, means responsive to the initiation of a call by any of said subscribers' lines for transmitting impulses over the trunk line to operate said first switch to seize the calling line, said means also effective to operate said last switch to characterize the calling line, another switch in the main exchange operated over the trunk line by the calling subscriber to characterize the wanted line, means normally effective to subsequently operate the device corresponding to the calling line, and means for rendering said last means ineffective if both of the switches in said main exchange 20 25 characterize the same line.

EUGEN JAUCH.
